UNITED STATES PATENT OFFICE

2,578,010

SUGAR SHAKER AND DISPENSER

Victor M. Llorens, Long Island City, N. Y.

Application September 27, 1947, Serial No. 776,524

4 Claims. (Cl. 222—448)

1

This invention relates to sugar shakers or dispensers.

It is an object of the present invention to provide a sugar dispenser whereby a measured quantity of sugar can be dispensed each time and wherein after the dispensing operation, the openings in the neck of the cover are automatically closed to prevent the inflow of dirt or insects.

It is another object of the present invention to provide in a sugar dispenser a closure device which is automatic in its operation once it has been moved in one direction by hand, which is of simple construction, inexpensive to manufacture and efficient in operation.

According to the invention, there has been provided a cover with a neck portion into which sugar can be dropped for being dispensed through openings at the end of the neck portion. Workable through the neck portion is a plunger adapted to engage with the sugar entering the neck portion to cause the same to be forced through the openings in the bottom of the neck portion as the sugar dispenser is inverted. Through the neck portion, there extends a rod-like member which is attached to the plunger entering the neck portion and which has externally of the cover, a handle portion by which the parts are pulled through the cover either according to one form of the invention against the action of the spring where the spring is located internally of the neck portion, or due to spring action where the spring is located externally of the neck portion. An external cover is provided on the rod in the one form of the invention to close the openings at the end of the neck when the internal member is held upwardly by the spring and in the other form of the invention, when the cover is the internal member. A flange, however, is provided in the other form on the rod externally thereof to provide means against which the spring can react and at the same time, to serve as a cover while the rod is temporarily held in a pushed-in position within the cover.

In a modified form of the invention, there are provided piston operated devices for effecting the actuation of the plunger and slide whereby the sugar will not be distributed onto the fingers while trying to dispense the same from the inverted sugar container. The piston operated devices are operated by plungers or slides above the opening of the neck portion and are brought together by pinching the same with the thumb and finger. The hand, operating the slide will not need to be disposed beneath the sugar opening.

For further comprehension of the invention,

2

and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a sugar dispenser having the cover with a neck portion, with the dispensing device within the neck portion.

Fig. 2 is an enlarged cross sectional view taken through the top of the dispenser and through the cover, showing the control arrangement according to one form of the invention.

Fig. 3 is a cross sectional view taken on line 3—3 of Fig. 2, of the top of the neck portion showing the openings therewithin, looking in the direction of the arrows thereof.

Fig. 4 is a detail elevational view of the rod with the members or flange portions thereon.

Fig. 5 is a cross sectional view of a dispenser in which the rod and members acting in the neck portion have been altered so that the spring is external of the top of the neck portion, according to a modified form of the invention.

Fig. 6 is a detail elevational view of the rod with members and flange portions thereon, as used in the form of the invention in Fig. 5.

Fig. 7 is a cross sectional view taken on line 7—7 of Fig. 8, looking upon the cover having the plunger operated devices at opposite sides of the same for effecting the operation of the slide and the plunger located within the cover.

Fig. 8 is a cross sectional view taken on line 8—8 of Fig. 7, showing the interior of the plunger operated devices and their working parts, looking in the direction of the arrows thereof.

Referring now to the figures, 10 represents a container which may be of glass or plastic on which there is a threaded portion 12 to which a screw cover 13 can be connected so as to close the open end of the container 10. The cover 13 is removable so that the container 10 can be filled with sugar. Thereafter, the cover is screwed on tightly and the sugar is dispensed through a neck portion 14 thereof closed at the top by a portion with holes 15 therein through which a rod 16 is slid.

This rod 16 is extended through a central opening 17 for this purpose. On the internal end of the rod, there is a plunger or operating member 18 adapted to be drawn through the neck portion 14 so as to force outwardly from the neck portion such sugar as has been collected therein through the openings 15. The rod has a handle 19 by which it is pulled downwardly and also

a flange or cover portion 21 which serves to cover the opening 15 when the dispenser is not in use and when the rod 16 is held internally by a spring 22 acting between the opening portion 15 and the plunger or working member 18.

To use the dispenser, the user inverts the same and pulls downwardly on the rod 16 by the use of the handle 19 so as to pull with it sugar which may have collected within the neck portion 14 when the dispenser was first inverted. If the rod 16 is pulled only a little way a continual flow of sugar may occur. Since the plunger 18 will not be at that time within the neck portion 14, the cover 21 will be pulled slightly from the opening 15.

Referring now particularly to Figs. 5 and 6, there is shown a modified form of the invention in which the operation is slightly different. The spring 22 is located externally of the cover 13 so as to normally maintain the plunger 18 in an extended position in the neck portion 14 and so that it serves normally as a cover over the opening 15. When sugar is to be dispensed, a rod 24 which is of less length than the rod 16 is depressed against the action of the spring 22 and then released and sugar will be forced out of the opening 15 by the plunger 18 automatically. The rod 24 is of less length than the rod 16 so that it does not protrude above the neck portion to any greater distance than the rod 16. The flange 21 thereon serves mainly as an abutment against which the spring will react and only temporarily as a cover when the rod 24 is pressed inwardly. It will not be a full cover as the spring 22 upon being compressed will consume space upon the rod. However, with the provision of a recess 25 in the cover 21, it can be brought into close engagement with the top of the neck portion inasmuch as the spring can be seated within the recess 25. This rod 24 also has a handle portion 19 thereon.

Referring now particularly to Figs. 7 and 8, there is shown a cover 31 having a neck portion 32 with the sugar dispensing openings 33 therein. The usual slide 16 extends upwardly thereinto, but cover flange 34 has ear projections 35 at opposite sides of the same adapted to be engaged by piston rods 36 housed within a cylinder 37 on the neck portion 32. These rods have pistons 38 and as operating plungers 39 are worked radially inwardly within chambers 41 against the action of spring 42, air will be forced through a small passage 43 into the cylinder 37 and against the piston 38 whereby to cause the piston rod 36 to be projected outwardly and to cause this cover flange 34 to be moved downwardly to uncover the openings 33 and to dispense the sugar. There are two of these plunger operated devices on the cover and the operating plungers 39 can be grasped by the thumb and finger of a hand and a squeezing action is effected upon them to cause the movement downwardly of the cover flange 34 whereby sugar will be dispensed from the openings 33.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A sugar dispenser comprising a main con-

tainer, a cover for the main container having a neck portion therein with a top thereover, said top having openings through which sugar may be dispensed and a central opening, a rod extending through the central opening in the top of the neck portion, a plunger on the inner end of the rod, said plunger adapted to be worked in the neck portion to force sugar out of the opening in the top part of the neck portion, a cover flange carried by the rod and adapted to close the openings in the top of the neck portion, spaced cylinders mounted on the sides of the neck portion, pistons slidably positioned within said cylinders, piston rods carried by said pistons and projected from said cylinders and connected with said cover flange, and manually operable means on said cover for moving said pistons within said cylinders in a direction to unseat said cover flange and permit the sugar to flow through said openings.

2. A sugar dispenser comprising a main container, a cover for the main container having a neck portion therein with a top thereover, said top having openings through which sugar may be dispensed and a central opening, a rod extending through the central opening in the top of the neck portion, a plunger on the inner end of the rod, said plunger adapted to be worked in the neck portion, a cover flange carried by the rod and adapted to close the openings in the top of the neck portion, spaced cylinders mounted on the sides of the neck portion, pistons slidably positioned within said cylinders, piston rods carried by said pistons and projected from said cylinders and connected with said cover flange, and manually operable means on said cover for moving said pistons within said cylinders in a direction to unseat said cover flange and permit the sugar to flow through said openings, and spaced ear projections formed on said cover flange and to which the projected ends of said piston rods are connected.

3. A sugar dispenser comprising a main container, a cover for the main container having a neck portion therein with a top thereover, said top having openings through which sugar may be dispensed and a central opening, a rod extending through the central opening in the top of the neck portion, a plunger on the inner end of the rod, said plunger adapted to be worked in the neck portion, a cover flange carried by the rod and adapted to close the openings in the top of the neck portion, spaced cylinders mounted on the sides of the neck portion, pistons slidably positioned within said cylinders, piston rods carried by said pistons and projected from said cylinders and connected with said cover flange, and manually operable means on said cover for moving said pistons within said cylinders in a direction to unseat said cover flange and permit the sugar to flow through said openings, said piston moving means comprising air chambers found on said cover one for each of said cylinders, passageways connecting each of said air chambers with its respective cylinder, and plungers slidable within said air chambers and having ends projecting therefrom to be manually pressed inward to force air from said chambers through said passageways into said cylinders to move said pistons in a direction to unseat said cover flange.

4. A sugar dispenser comprising a main container, a cover for the main container having a neck portion therein with a top thereover, said top having openings through which sugar may be dispensed and a central opening, a rod ex-

tending through the central opening in the top of the neck portion, a plunger on the inner end of the rod, said plunger adapted to be worked in the neck portion, a cover flange carried by the rod and adapted to close the openings in the top of the neck portion, spaced cylinders mounted on the sides of the neck portion, pistons slidably positioned within said cylinders, piston rods carried by said pistons and projected from said cylinders and connected with said cover flange, and manually operable means on said cover for moving said pistons within said cylinders in a direction to unseat said cover flange and permit the sugar to flow through said openings, said piston moving means comprising air chambers found on said cover one for each of said cylinders, passageways connecting each of said air chambers with its respective cylinder, and plungers slideable within said air chambers and having ends projecting therefrom to be manually pressed inward to force air from said chambers through said passageways into said cylinders to move said pistons in a direction to unseat said cover flange,

and springs within said chambers and bearing against the inner ends of said plungers retaining them in an operative extended position.
